UNITED STATES PATENT OFFICE

164,135

TELEPHONE BOOK MONOCLE

Annie B. Rogers, Palestine, Tex.

Application March 2, 1951, Serial No. 14,359

Term of patent 7 years

(Cl. D57—1)

To all whom it may concern:

Be it known that I, Annie B. Rogers, a citizen of the United States, residing at Palestine, in the county of Anderson and State of Texas, have invented a new, original, and ornamental Design for a Telephone Book Monocle, of which the following is a specification, reference being had to the accompanying drawing, forming part thereof.

The figure is a perspective view of a telephone book monocle showing my new design, the opposite side presenting substantially the same appearance as the side shown.

I claim:

The ornamental design for a telephone book monocle, substantially as shown and described.

ANNIE B. ROGERS.
